CLAIM

The ornamental design for a display device for a computer, as shown and described.

DESCRIPTION

FIG. 1 is a right hand view of a display device for a computer.

FIG. 2 is a left hand view thereof;

FIG. 3 is a front view thereof;

FIG. 4 is a rear view thereof;

FIG. 5 is a top view thereof; and

FIG. 6 is a bottom view thereof.

The components that would be seen through the hole at the bottom of FIG. 6 have been omitted for ease of illustration.

FIG. 1

FIG. 2

FIG. 3

FIG. 4

FIG. 5

FIG. 6
